UNITED STATES PATENT OFFICE.

WILLIAM WHEELER, OF FORESTON, MARYLAND.

DESIGN FOR A SAFETY HITCH-RING.

SPECIFICATION forming part of Design No. 31,189, dated July 11, 1899.

Application filed March 11, 1899. Serial No. 708,768. Term of patent 14 years.

To all whom it may concern:

Be it known that I, WILLIAM WHEELER, a citizen of the United States, residing at Foreston, in the county of Baltimore and State of Maryland, have invented a new and original Design for a Safety Hitch-Ring, of which the following is a specification.

This invention relates to a new and original design for a safety hitch-ring; and it has for its object to provide a design of this character that shall be both useful and ornamental.

The leading feature of the design resides in a ring or hook provided with a substantially S-shaped body, having both ends deflected on a curve transversely of the body at the same side thereof, the terminals of said deflected ends being provided with shouldered conical tips pointing in opposite directions.

A minor feature of the design resides in the deflected ends of the S-shaped body being disposed at an acute angle to the plane of the body.

In the drawings, Figure 1 is a perspective view of the safety hitch-ring embodying the

herein-described design. Fig. 2 is a plan view 25 thereof. Fig. 3 is a cross-sectional view on the line 3 3 of Fig. 2.

Referring to the accompanying drawings, the numeral 1 designates the body of a ring or hook, which is substantially S-shaped and 30 round in cross-section. The said S-shaped body 1 has both ends 2 thereof deflected on a curve transversely of the body and projecting therefrom at the same side thereof. The terminals of said deflected ends 2 are disposed 35 at an acute angle to the plane of the body and are provided with shouldered conical tips 3, respectively, pointing in opposite directions.

What is claimed is—

The design for a safety hitch-ring, herein 40 shown and described.

In testimony that I claim the foregoing as my own I have hereto affixed my signature in the presence of two witnesses.

WILLIAM WHEELER.
